[57] ABSTRACT

[22] Filed: Aug. 2, 1973

An elongate bolt having a head at its upper end and a threaded lower end is mounted through a sheet steel member of a steel floor deck. The threaded lower end may comprise a stud formation or an interior threaded socket. The bolt is mounted in a hole drilled in the horizontal sheet steel member and is held in place by a thin flexible sheath member engaging the bolt below the sheet of steel and a flat leaf spring engaging the upper surface of the sheet of steel. When concrete is poured on the upper surface of the horizontal sheet steel member and set, it will embed the upper portion of the bolt which may have additional structural means to increase the embedded area. Prior to pouring, however, the upper portion of the bolt is yieldable by reason of the flat leaf spring but recoverable to a position perpendicular to the plane of the sheet steel member.

FIG. 2

FIG. 6

FIG. 4

FIG. 7

FIG. 3

FIG. 8

HANGER INSERT FOR STEEL FLOOR DECK

This is a continuation of application Ser. No. 214,226, filed Dec. 30, 1971, now abandoned.

BACKGROUND OF THE INVENTION

The invention herein is concerned with apparatus which is intended to be installed in the deck of a building during the construction thereof to provide depending hangers below the deck. For example, through the use of the hanger inserts of the invention, one may support pipes and conduits, automatic sprinkler apparatus, electrical fixtures, and any other apparatus which would normally be depending from a ceiling.

What will be referred to herein as deck construction or decking is a type of construction which is extensively used for forming the floors of large steel frame buildings of multiple stories. The floor of one level is defined on the upper surface of a given deck while the ceiling of the lower level is defined by the lower surface of the same deck.

Although there are several types of deck construction in use today in the construction of large buildings, one of the most important of these is the steel floor deck due to its presently increased use in large steel frame buildings of multiple stories.

Fluted or corrugated sheet steel is utilized as a floor base and filled with a substantial layer of concrete poured in situ. Utility service conduits are laid in suitable formations of the sheet steel member prior to pouring concrete upon the upper surface of the member. There may be outlets for these conduits on the upper surfaces of the concrete layer which are prelocated in the concrete or otherwise identified to be used at a later time. The bottom of this layer of concrete is in intimate contact with the steel base whose underside is exposed below as the ceiling for the lower level. The resulting deck structure is strong and substantially fireproof.

In the planning of a building, structures to be supported from the bottom of the deck are best located and inserts installed in the sheet steel prior to pouring the concrete. The only alternative is to attempt to effect the installation from below after the concrete has set. This is a difficult and expensive technique. One must first cut or drill through the layer of steel and then use some form of concrete anchor.

The invention contemplates a type of hanger insert which obviates some problems arising in any attempt to provide hanger inserts for pre-installation.

First, the insert must be simple and strong so that it can be installed effectively and easily. Also, it must be economical and result in a strong installation below the deck after the concrete has set.

Secondly, the insert must not readily be pulled out or permanently bent over prior to the pouring of the concrete. This is important because until the concrete has been fully poured, workmen may step on the inserts, accidentally kick them, or structures to be preset into the concrete may be moved against the inserts. The latter structures might be utility conduits or reinforcing rods.

Certain other problems in connection with such hanger inserts are solved by the invention as will be seen.

SUMMARY OF THE INVENTION

The hanger insert comprises an elongate boltlike

body having its lower end constructed to secure a structural member thereto, its upper end provided with a head or other enlarged means to be embedded in concrete, the boltlike member being secured to a horizontal sheet steel member with a flexible or yieldable connection. A thin flexible sleeve-like member of sheet metal or elastomeric material is secured to the boltlike member below the sheet steel member and a flat leaf spring is engaged against the upper surface of the sheet steel member and held to the elongate boltlike member.

Different means are utilized to assemble the several parts of the hanger so that it may readily swing or yield and return to its original vertical position perpendicular to the horizontal sheet steel member even though struck or moved by a workman or an object prior to the pouring of the concrete.

Once the concrete has been poured, the upper portion of the boltlike member is permanently embedded and the lower end thereof extends below the sheet steel member and is available for securement of structural members thereto. Either a stud arrangement or a threaded socket may be provided.

BRIEF DESCRIPTION OF THE DRAWING

FIG. 1 is a fragmentary sectional view taken through a portion of steel floor deck having a hanger insert constructed according to the invention installed therein, the latter being shown, for the most part, in elevation;

FIG. 2 is a sectional view taken through the hanger insert of FIG. 1 generally along the line 2-2 and looking upwardly;

FIG. 3 is a perspective view of the sheath member of the structure of FIG. 1;

FIG. 4 is a fragmentary view illustrating a modified form of the invention using a sheath member which is different from that illustrated in FIG. 1;

FIG. 5 is a side elevational view with portions in section as showing a further modified form of the invention;

FIG. 6 is a bottom plan view of the sleeve member of FIG. 5;

FIG. 7 is a sectional view through the sleeve member of FIG. 6 taken generally along the line 7-7 and in the direction indicated; and

FIG. 8 is a view similar to that of FIG. 1 showing a further modified form of the invention.

DESCRIPTION OF THE PREFERRED EMBODIMENT

As previously explained, the hanger insert of the invention is designed to be installed in decking of the type which involves poured concrete prior to the pouring of the concrete so that the setting of the concrete will permanently anchor the insert in the deck.

In FIG. 1 there is illustrated a portion of a steel floor deck comprising a horizontal sheet steel member 10 having a layer of concrete 12 of substantial thickness above the same and in intimate contact therewith. The hanger insert of the invention is designated generally by the reference character 14 and is shown partially above and partially below the horizontal sheet steel member 10.

The insert 14 comprises an elongate boltlike member having an upper cylindrical body portion 16 and a lower cylindrical body portion 18, the lower body portion 18 protruding below the sheet steel member 10

and in this version of the invention having an internal threaded socket 20 opening to the bottom end of the lower body portion 18. The upper end of the upper portion 16 has a relatively large head 22 integral therewith and if desired, for the purpose of adding anchoring area, any suitable member may be engaged to said upper portion 16 so that the anchoring in the concrete 12 will be more effective. In this case, a large cotter pin 24 having a lateral bend 26 is snapped onto the upper body portion 16 as shown.

A sheath member 28 is provided to secure the bolt-like member to the sheet steel member 10. The sheath member 28 is best illustrated in FIG. 3. It is a sleeve-like structure formed from thin sheet spring steel and has a cylindrical body 30 open at the bottom as shown at 32 and provided with an axial split 34 thereby giving the sheath member bodily resilience. At its upper end there are provided flangelike ears 36 and a plurality of spring fingers 38 spaced below the ears 36. The spring fingers are formed by punching the same out of slots 40 provided in the body 30 of the sheath member and have an external bend 42 that protrudes outwardly of the body and an internal edge 44 on the interior of the body 30.

In installing the insert, first a hole is drilled in the horizontal sheet steel member 10 as shown at 46, this hole being of a diameter slightly less than the diameter of the body portion 30. It could even be the same diameter or slightly larger so that the split 34 provides sufficient space for compressing the sheath 28 in order to force it into the hole 46. The outwardly extending bends 42 of the fingers 38 must be compressed in forcing the sheath member 28 downwardly through the hole 46 and they spring back when the ears 36 engage on the upper surface of the sheet steel member 10 thereby resiliently clamping the sheath member 28 in the position shown in FIG. 1.

The upper portion 16 of the boltlike member is provided adjacent its center with protuberances 48 which may be formed simply by pinching the metal at this point. A flat leaf spring 50 which is bowed in a concavely downward direction has a central opening 52 and is fitted to the portion 16 of the boltlike member. The ends are slightly turned up at 51. The lower portion 18 of the boltlike member is inserted through the opening 52 and thereafter pushed into the sheath member 28. The lower end of the sheath member 28 may have inturned lips as shown at 54 to limit the extent to which the lower portion 18 may enter, or there may be a groove such as shown at 56 into which the fingers 38 may drop.

After the insert has been assembled as shown in FIG. 1, it is capable of being rocked or otherwise moved to a certain extent by workmen kicking or stepping on the same and it will recover to its vertical position perpendicular to the plane of the sheet steel member 10. When the concrete is poured around the same, it will become permanently embedded as shown in FIG. 1.

FIG. 4 illustrates a modified form of the invention which utilizes a sheath member 28' that has an extension 60 terminating in an end cap 62. The end cap 62 limits the extent to which the lower portion 18 of the boltlike member 14 may be inserted and it also protects the threaded socket 20 until use at which time the workmen may break off the cap 62 or bend the same aside in order to have access to the threaded socket.

FIG. 5 illustrates a relatively simple form of the invention which comprises a threaded bolt 70 having a

conventional head 72 with a large washer 74 connected to the head to give a larger area of embedment. The same type of leaf spring as previously described is used, this being shown at 76, having a central opening 78 which engages the upper body 82 of the bolt 70, its position being determined by the nut 80 engaging the upper threaded portion 83 of the bolt 70. The lower end of the bolt passes through an opening 84 in the sheet steel member 86 and a sheet metal sleeve-like nut 88 is engaged on the lower portion 90 of the bolt.

As best seen in FIGS. 6 and 7, the nut 88 has a body portion 92 which is generally cylindrical, a plurality of circumferentially spaced flared ears 94, and a pair of internal thread-engaging tangs 96. The nut 88 is made out of resilient sheet metal. Through the use of the tangs 96, the nut may be screwed onto the threaded portion 90 and by virtue of the resilience of the flared ears 94, the nut may be pushed through from the top of the sheet metal member 86 through the hole 84 to the position shown so that it is unnecessary to manipulate anything from the bottom of the sheet metal member 86. In this way, the workman installing the insert, assembles the same practically as shown and forces the bottom end together with the nut 88 through the hole 84. The ears 94 contract and then spring outwardly after passing through the hole 84. The firmness of the leaf spring 76 is easily adjusted by taking up or releasing the nut 80. As in the case of the previously described leaf spring, the ends 98 are slightly bent to enable a considerable latitude of movement. If the insert is stepped on, it will recover by virtue of the leaf spring, or if it is struck from the side laterally, it will erect itself when the pressure is removed.

In this case, the portion 90 acts like a stud which is protruding from the bottom of the sheet steel member 86 which forms the ceiling for the level below the deck. Either a structural member may be secured to the portion 90 by a conventional nut, or an elongate adapter nut 100 may be screwed onto the end 90 to provide a socket in its bottom end to receive threaded structural members.

FIG. 8 illustrates a modified form of the invention similar to those forms shown, but using a sheath member 110 which is molded from an elastomer such as natural or synthetic rubber or elastic resins. The bolt 14' has an upper body portion 16 and a lower body portion 18' which in this case is an externally threaded stud end separated from the upper body portion by a shoulder 112. The sheath member 110 has a relatively thin wall 114 the exterior of which is tapered as shown with a plurality of ridges 115 forming grooves 116 of increasing diameter, upwardly. The bolt 14' is inserted into the sheath 110 which tightly engages the stud end 18', the spring 50 being in place. The lower end 118 of the sheath is introduced into the hole 46 previously cut in the steel deck 10 from above. The workman pushes the sheath 110 and stud end 18' into the hole until the lips of the hole 46 lockingly engage in one of the grooves 116 while the spring 50 is engaged against stops 48 under some tension.

The structure of FIG. 8 functions like the others. When the concrete is set, the elastomeric wall 114 is all that is exposed below the deck. The stud end 18' is protected until the workman wants to use it. He can then pull off the part of the sheath 110 protruding or cut it away. Prior to pouring of the concrete the bolt 14' will readily yield laterally if struck and will also provide a

degree of axial yielding as well, recovering to its vertical position when the disturbing force is removed.

Modifications of the invention may be made without departing from the spirit or scope of the same as defined in the appended claims.

What it is desired to secure by Letters Patent of the United States is:

1. A hanger insert for installation in decking including a layer of concrete and a sheet member supporting the concrete prior to its being poured, the insert comprising:

A. an elongate metal member having a bottom end and a top end with stop means located therebetween,

B. means for supporting said elongate metal member in a disposition passing through a hole in a sheet member which is adapted to have concrete poured onto the upper surface of the sheet member, with the bottom portion of the elongate metal member protruding below the sheet member and the top portion of the elongate metal member protruding above the sheet member,

C. said elongate metal member including structure to enable the securement of a structural member from the bottom portion thereof which structural member is adapted to depend from the decking to be formed, and

D. a leaf spring formed of flat spring stock bowed about a central area and loosely mounted through said central area on said elongate member to have its concave surface facing the lower portion of the elongate member, said leaf spring being held between the stop means on said elongate member and the upper surface of said sheet member, said leaf spring providing a yieldable connection between said hanger insert and sheet member prior to the setting of said concrete and enabling the hanger insert to absorb the shock attendant upon the influx of fluid concrete and to restore the elongate metal member to an erect position before the concrete sets.

2. The hanger insert as claimed in claim 1, in which said stop means comprise a formation on said upper portion integral with said elongate metal member, said leaf spring has a central opening in which said elongate metal member engages, and said formation is larger than said opening.

3. The hanger insert as claimed in claim 1, in which the elongate metal member is a threaded bolt, the leaf spring has a central opening in which said bolt is engaged, and the stop member is a nut, the structure to enable securement comprising the bottom threaded end of said bolt.

4. The hanger insert as claimed in claim 1, in which the upper end of said elongate metal member comprises an enlarged structure to provide embedment area greater than the cross-sectional area of said elongate metal member.

5. The hanger insert as claimed in claim 1, in which the means for supporting the elongate member include a sleeve-like sheet metal member secured on said lower portion and adapted to engage the bottom surface of said sheet member and clamp same between said leaf spring and itself.

6. The hanger insert as claimed in claim 5, in which the ends of the leaf spring are turned slightly toward the upper portion of the elongate member.

7. A hanger insert for installation in decking including a layer of concrete and a sheet member supporting the concrete prior to its being poured, and said insert comprising:

5 A. an elongate metal member having a bottom end and a top end,

B. means for supporting said elongate metal member in a disposition passing through a hole in a sheet member which is adapted to have concrete poured onto the upper surface of the sheet member, with the bottom portion of the elongate metal member protruding below the sheet member and the top portion of the elongate metal member protruding above the sheet member,

C. said elongate metal member including structure to enable the securement of a structural member from the bottom portion thereof which structural member is adapted to depend from the decking to be formed,

D. a leaf spring formed of flat spring stock bowed about a central area and loosely mounted through said central area on said elongate member to have its concave surface facing the lower portion of the elongate member, said bowed portion being lockable between the stop means on said elongate member and the upper surface of said sheet member to provide a yieldable connection between said hanger insert and sheet member prior to the setting of said concrete, said elongate member having stop means establishing the location of mounting said leaf spring thereon, and

E. said supporting means including a hollow sheath member telescopically engaged with said elongate metal member along a portion of the length thereof, the sheath member being adapted to be inserted through a predrilled hole in said sheet member of a size to accommodate said sheath member, the sheath member having means at the upper end thereof adapted resiliently to engage within the hole of said sheet member to resist the sheath member's passing through or being pulled from said sheet member while at the same time providing a yieldable connection therewith, and the lower end of the sheath member being constructed to provide across to the bottom end of the elongate metal member after the concrete has been poured and set.

8. The hanger insert as claimed in claim 7, in which the said sheath member and elongate metal member have cooperating means limiting the extent to which the elongate member is telescopically insertable into the sheath member.

9. The hanger insert as claimed in claim 7, in which said sheath member is of elastomeric material.

10. The hanger insert as claimed in claim 7, in which the sheath member is made of sheet metal, and the means at the upper end thereof comprise an overhang adapted to engage the upper surface of the sheet member and means spaced below said overhang adapted resiliently to engage with said sheet member on the lower surface thereof.

11. The hanger insert as claimed in claim 10, in which said means adapted resiliently to engage said sheet member comprises a set of fingers circumferentially arranged around the sheath member and having a given spacing from the overhang thereof whereby when inserted through said predrilled hole the fingers

will be depressed and will then spring outwardly after passing through said hole whereby to sandwich the sheet member between said overhang and said fingers.

12. The hanger insert as claimed in claim 9, in which the means at the upper end of the sheath member comprise groove means formed in the exterior surface thereof.

13. The hanger insert as claimed in claim 12, in which the sheath member is tapered and the groove means are of increasing diameter along the length thereof.

14. A hanger insert for installation in decking including a layer of concrete and a sheet member supporting the concrete prior to its being poured, the insert comprising:

A. an elongate metal member having a bottom end and a top end,

B. means for supporting said elongate metal member in a disposition passing through a hole in a sheet member which is adapted to have concrete poured onto the upper surface of the sheet member, with the bottom portion of the elongate metal member protruding below the sheet member and the top portion of the elongate metal member protruding above the sheet member,

C. said elongate metal member including structure to enable the securing of a structural member from the bottom portion thereof which structural member is adapted to depend from the decking to be formed,

D. a leaf spring formed of flat spring stock bowed about a central area and loosely mounted through said central area on said elongate member to have its concave surface facing the lower portion of the elongate member, said bowed portion being lockable between the stop means on said elongate member and the upper surface of said sheet member to provide a yieldable connection between said hanger insert and sheet member prior to the setting of said concrete, said elongate member having stop means establishing the location of mounting said leaf spring thereon,

E. the means for supporting the elongate member including a sleevelike sheet metal member secured on said lower portion and adapted to engage the bottom surface of said sheet member and clamp same between said leaf spring and itself,

F. the bottom portion of said elongate member is threaded and the sleevelike sheet metal member has thread-engaging tangs screwed onto said threaded end, and

G. the sleevelike sheet metal member having flared resilient ears, capable of contracting while said sleevelike sheet metal member is forced through the hole in said sheet member and recovering thereafter.

15. The hanger insert as claimed in claim 14, in which the position of the stop means is adjustable.

16. A hanger insert for installation in sheet steel decking comprising:

A. a boltlike member having a headed portion at one end and means for securing of a structural mem-

ber at the other end,

B. a flat bowed leaf spring having a central passageway between outer bowed ends, the bolt-like member being engaged in the passageway, the bow being concave toward said other end,

C. stop means limiting movement of the spring along the central passageway toward said one end, and

D. sleevelike means attached to said other end for mounting said boltlike member in a hole in a horizontal member of sheet steel with the bow ends of the leaf spring engaging the top of said horizontal member and the boltlike member making a yieldable but recoverable connection with said horizontal member.

17. The hanger insert as claimed in claim 16, in which the sleevelike means comprises a tapered, molded, elastomeric sleeve having exterior annular groove means at its upper end of different sizes.

18. The hanger insert as claimed in claim 16, in which the sleevelike means comprises a sheet metal nut adapted to engage the bottom of said horizontal member.

19. The hanger insert as claimed in claim 18, in which the boltlike member is a threaded bolt and the securing means is the threaded end opposite said headed portion.

20. In combination with the sheet steel member of a steel floor deck, a hanger insert engaged in a predrilled hole in said sheet steel member with a part of the insert disposed above the sheet steel member and other part of the insert disposed below the sheet steel member, said insert comprising:

A. an elongate cylindrical member of metal having an upper portion and a lower portion, the upper portion having a head adapted to be embedded in concrete poured on the upper surface of said sheet steel member, the lower portion having a formation to enable the securing of a structural member thereto depending from the bottom of said sheet steel member,

B. a flat leaf spring having a central connection with the upper portion of said cylindrical member and stop means limiting the movement of the spring toward said head, the spring being bowed concavely toward the lower portion with its ends engaging the upper surface of said sheet steel member, and

C. a sleevelike sheet metal member secured to the lower portion in telescoping engagement and effective in cooperation with the spring to hold said cylindrical member in a yieldable but recoverable disposition normal to the plane of said sheet steel member.

21. The combination as claimed in claim 20, in which the distance between the stop means and sleevelike sheet metal member is such as to put the leaf spring under at least partial tension and the tension is adjustable.

22. The combination as claimed in claim 20, in which the cylindrical member is a threaded bolt, the stop means is a nut and the sleevelike member is a sheet metal nut.
